UNITED STATES PATENT OFFICE

2,627,917

VENETIAN BLIND

George R. Lind, St. Joseph, Mich.

Application February 23, 1951, Serial No. 212,397

10 Claims. (Cl. 160—173)

1

This invention relates to improvements in Venetian blinds.

The main objects of this invention are:

First, to provide a Venetian blind bottom bar which may be quickly and easily connected to the suspending tapes of the ladder.

Second, to provide a structure having these advantages which may be economically produced and at the same time is attractive in appearance and permits the disconnection of the bottom bar from the ladder tapes for laundering or cleaning or renewal of the tapes.

Objects relating to details and economies of the invention will appear from the description to follow. The invention is pointed out in the claims.

A preferred embodiment of the invention is illustrated in the accompanying drawing, in which:

Fig. 1 is a fragmentary perspective view of a Venetian blind embodying my invention.

Fig. 2 is an enlarged fragmentary view in section on a line corresponding to line 2—2 of Fig. 4.

Fig. 3 is a fragmentary perspective view with the top bar member omitted.

Fig. 4 is an enlarged transverse section on a line corresponding to line 4—4 of Fig. 2.

Fig. 5 is an enlarged fragmentary plan view, with the top member omitted, further illustrating the relation of certain of the parts, a fragment of a ladder tape being shown in section.

Fig. 6 is a perspective view of the clamp member.

In the accompanying drawing, 1 represents the slats of a Venetian blind and 2—2 the suspending tapes which are provided with slat supporting cross straps, not illustrated. These tapes 2—2 are preferably connected at their lower ends to provide a loop 3. The bottom bar of my invention designated generally by the numeral 4 comprises the bottom member 5 of curved upwardly facing channel section and having inturned flanges 6 on its edges. The flanges 6 have slots 7 therein adapted to receive the tapes 2, the end edges of the slots being notched or conformed to provide keepers 8.

The tape clamp member 9 is formed as a sheet metal stamping and has downwardly offset upwardly facing U-shaped springable arms 10 on its side edges. The outer portions 11 of these arms are adapted to spring or snap under the keepers 8. These arms are of such width that when the clamp member is disposed within the loop of the suspending tapes as shown in the drawing and the arms springably engaged with the keepers, the

tapes are clamped against the inner side of the bottom member 5. However, if for any reason there is not effective clamping engagement between the bottom member 5 and the arms as is indicated in the drawings, the tapes cannot be withdrawn where the lower ends are connected to form the loop 3. One arm of the clamp member is in the embodiment illustrated extended to provide a finger piece 12 which facilitates the releasing of the clamp.

The arms of the clamp are provided with in-turned lugs 13 adapted to receive and retainingly engage the top member 14 which is in the embodiment illustrated of downwardly facing curved section and may be sprung to engage with the lugs and is retained in engagement therewith by its inherent springability.

The clamp member 9 is provided with a key-hole slot 15 adapted to receive the suspending cord 16, the cord 16 being provided with a knot 17 which may be passed through the enlarged part of the slot 15 and slipped under the restricted part of the slot. The top member 14 is provided with a cord receiving slot 18 which is aligned with the restricted portion of the slot 15 when the top member is assembled thus preventing the disengagement of the lifting cord from the bottom bar. The load on the clamp member does not tend to disengage it from the bottom member 5 inasmuch as the springable arms are engaged under the flanges and in fact, the load tends to urge them more securely to engaged position, the flange engaging portion of the arms being inclined outwardly as shown in Fig. 4.

The parts of my invention may be very economically produced and they are quickly assembled to secure the bottom bar to the ladder tapes and the bottom bar may be quickly released should occasion require as for cleaning or renewal of the tapes.

I have illustrated my invention in a highly practical commercial embodiment thereof. I have not attempted to illustrate or describe certain embodiments or adaptations which I contemplate as it is believed that this disclosure will enable those skilled in the art to embody or adapt my invention as may be desired.

Having thus described my invention, what I claim as new and desire to secure by Letters Patent is:

1. The combination in a Venetian blind including slat suspending tapes connected at their lower ends to provide a loop, of a bottom bar comprising a bottom member of curved upwardly facing channel section and having inturned edge

flanges, said flanges having slots therein receiving the tapes with the loop thereof within the bottom member, the end edges of the slots being notched to provide inwardly facing keepers, a clamp member having downwardly offset upwardly facing U-shaped springable tape clamping arms on its side edges disposed in said bottom member and within the loop of the tapes with its arms within said slots and in springable retaining engagement with said keepers, said arms of said clamp member being provided with inturned lugs, one of said arms being extended to provide a finger piece projecting above the bottom member, said clamp member having a keyhole slot therein adapted to receive a suspending cord, and a top member of downwardly facing curved section disposed with its edges upon said inturned flanges of said bottom member and springably engaged with said lugs on said clamp member, said top member having an opening aligned with the reduced end of said keyhole slot in said clamp member to receive the suspending cord and prevent its disengagement from the keyhole slot.

2. The combination in a Venetian blind including slat suspending tapes connected at their lower ends to provide a loop, of a bottom bar comprising a bottom member of upwardly facing channel section having inturned edge flanges, said flanges having slots therein receiving the tapes with the loop thereof within the bottom member, the end edges of the slots being notched to provide inwardly facing keepers, a clamp member having downwardly offset upwardly facing U-shaped springable tape clamping arms on its side edges disposed in said bottom member and within the loop of the tapes with its arms within said slots and in springable retaining engagement with said keepers, said arms of said clamp member being provided with inturned lugs, said clamp member having a keyhole slot therein adapted to receive a suspending cord, and a top member of downwardly facing curved section disposed with its edges upon said inturned flanges of said bottom member and springably engaged with said lugs on said clamp member, said top member having an opening aligned with the reduced end of said keyhole slot in said clamp member to receive the suspending cord and prevent its disengagement from the keyhole slot.

3. The combination in a Venetian blind including slat suspending tapes connected at their lower ends to provide a loop, of a bottom bar comprising a bottom member of curved upwardly facing channel section and having inturned edge flanges, said flanges having slots therein receiving the tapes with the loop thereof within the bottom member, the end edges of the slots being notched to provide inwardly facing keepers, a clamp member having downwardly offset upwardly facing U-shaped springable tape clamping arms on its side edges disposed in said bottom member and within the loop of the tapes with its arms within said slots and in springable retaining engagement with said keepers, said arms of said clamp member being provided with inturned lugs, one of said arms being extended to provide a finger piece projecting above the bottom member, and a top member disposed with its edges upon said inturned flanges of said bottom member and springably engaged with said lugs on said clamp member.

4. The combination in a Venetian blind including slat suspending tapes connected at their lower ends to provide a loop, of a bottom bar

comprising a bottom member of upwardly facing channel section having inturned edge flanges, said flanges having slots therein receiving the tapes with the loop thereof within the bottom member, the end edges of the slots being notched to provide inwardly facing keepers, a clamp member having downwardly offset upwardly facing U-shaped springable tape clamping arms on its side edges disposed in said bottom member and within the loop of the tapes with its arms within said slots and in springable retaining engagement with said keepers, said arms of said clamp member being provided with inturned lugs, and a top member disposed with its edges upon said inturned flanges of said bottom member and springably engaged with said lugs on said clamp member.

5. The combination in a Venetian blind including slat suspending tapes connected at their lower ends to provide a loop, of a bottom bar comprising a bottom member of curved upwardly facing channel section and having inturned edge flanges, said flanges having slots therein receiving the tapes with the loop thereof within the bottom member, the end edges of the slots having inwardly facing keepers thereon, and a clamp member having downwardly offset upwardly facing U-shaped springable tape clamping arms on its side edges disposed within the loop of the tapes with its arms within said slots and in springing retaining engagement with said keepers, one of said arms being extended to provide a finger piece projecting above the bottom member.

6. The combination in a Venetian blind including slat suspending tapes connected at their lower ends to provide a loop, of a bottom bar comprising a bottom member of curved upwardly facing channel section and having inturned edge flanges, said flanges having slots therein receiving the tapes with the loop thereof within the bottom member, the end edges of the slots having inwardly facing keepers thereon, and a clamp member having downwardly offset upwardly facing U-shaped springable tape clamping arms on its side edges disposed within the loop of the tapes with its arms within said slots and in springing retaining engagement with said keepers.

7. A bottom bar for Venetian blinds including slat suspending tapes comprising a bottom member of upwardly facing channel section and having inturned edge flanges, said flanges having tape receiving slots therein, the end edges of the slots being notched to provide inwardly facing keepers, a clamp member having downwardly offset springable tape clamping arms on its side edges disposed within said slots in springable retaining engagement with said keepers, the arms of said clamp member being provided with inturned lugs, said clamp member having a keyhole slot therein adapted to receive a suspending cord, and a top member disposed upon said bottom member with its edges retainingly engaged with said lugs on said clamp member, said top member having a suspending cord receiving opening aligned with the said slot in said clamp member, said top member acting to prevent the disengagement of the suspending cord from said clamp member.

8. A bottom bar for Venetian blinds including slat suspending tapes comprising a bottom member of upwardly facing channel section and having inturned edge flanges, said flanges having opposed tape receiving slots extending outwardly

from their inner edges, the end edges of the slots being notched to provide inwardly facing keepers, and a clamp member having downwardly offset upwardly facing U-shaped springable tape clamping arms on its side edges disposed within said slots in springable retaining engagement with said keepers and in clamping engagement with tapes disposed within the bottom member between the wall thereof and bights of the clamping arms.

9. A bottom bar for Venetian blinds including slat suspending tapes comprising a bottom member of upwardly facing channel section and having inturned edge flanges, said flanges having tape receiving slots therein, a tape clamp member disposed within said bottom member and having springable arms retainingly engaging within said flanges, said clamp member being provided with opposed lugs and having a slot therein adapted to receive a suspending cord, and a top member disposed upon said bottom member and retainingly engaged by said lugs on said clamp member, said top member acting to prevent the disengagement of the suspending cord from said clamp member.

10. A bottom bar for Venetian blinds includ-

ing slat suspending tapes comprising a bottom member of upwardly facing channel section and having inturned edge flanges, said flanges having opposed tape receiving slots extending outwardly from their inner edges, and a tape clamp member disposed within said bottom member and having springable upwardly facing U-shaped clamping arms retainingly engaging within said slots in said flanges with the bights of the arms in clamping engagement with tapes disposed within said bottom member and through said slots.
